UNITED STATES PATENT OFFICE

SAMUEL W. AVIS, OF GREENWICH, CONNECTICUT, AND MALCOLM H. AMES, OF WALTHAM, MASSACHUSETTS, ASSIGNEES TO RUSSELL, BURDSALL & WARD BOLT & NUT COMPANY, OF PORT CHESTER, NEW YORK, A CORPORATION OF NEW YORK

TOOL HOLDER FOR NUT MAKING APPARATUS

Application filed March 19, 1930. Serial No. 437,081.

This invention relates to apparatus for forming nut blanks. In a copending application of Samuel W. Avis, serial No. 287,795, filed June 23, 1928, there is described and claimed a process of making nut blanks by cold punching in which the volume of the blank is substantially equal to the volume of the finished nut. The apparatus herein described and claimed is particularly suitable for use in practicing the Avis process.

In the manufacture of nut blanks by the cold punch process now in use, the waste or scrap amounts to substantially 50 percent of the material. As more fully described in the Avis application, this waste can be substantially eliminated by forcing outwardly a metal blank of substantially the same volume as the volume of the finished nut to form the central opening of the nut, and produce a blank of the desired size. To carry out this operation on a commercial scale, it is necessary to form the central opening in a series of punching operations, and the present machine is designed for the purpose of performing this series of punching operations simultaneously on a plurality of blanks carried by a dial or other suitable supporting member, said dial having a step by step movement, whereby the production of the machine may compare favorably with the production of a machine of the prior art in which the central opening is formed in a single punching operation.

We accordingly provide a machine consisting of a dial having a plurality of die pockets, together with means for imparting a step by step motion to the dial. A tool holder and stripper block is arranged on each side of the dial and means are provided for reciprocating them to a closed position and to an open position. The dial driving means is synchronized with the reciprocating drive means to move the dial while the tool holders and stripper blocks are in open position. The tool holders are provided with a number of punches or other tools corresponding in number to the number of die pockets in the dial, so that at each closing of the tool holders, a separate operation may be performed on a nut blank in each pocket. Suitable

means are provided for automatically feeding the blanks to the dial at the first station, the feeding mechanism being actuated upon each movement of the reciprocating parts of the machine to feed one blank, and means are provided for ejecting the finished blank from the dial.

The machine is also provided with suitable safety means for automatically disengaging the dial from the drive mechanism upon breakage of any of the punches, or displacement of the blanks from the die pockets together with means for returning the dial to its last operating position so that the dial pockets will be in alignment with the punches, and injury to the apparatus will be prevented.

In the accompanying drawings we have shown one form of the invention.

In the drawings:
 Fig. 1 is a plan view; 70
 Fig. 2 is a side elevation; 75
 Fig. 3 is a vertical, sectional view on line 3—3 of Fig. 1 on an enlarged scale;

Fig. 4 is a plan view on the same scale as Fig. 3 with the top casting removed, and with parts broken away for clearness; and

Fig. 5 is a vertical, sectional view on line 5—5 of Figs. 2 and 3 on the same scale as Fig. 3.

Referring to the drawings, the reference numeral 1 designates the lower portion of the main housing. The upper portion 2 is arranged over the lower portion of the housing and provided with a cover 3. The machine is driven by means of a motor 4 (see Fig. 1) arranged at one end of the machine and supported on the upper section 2 of the housing. The motor is provided with a motor shaft 5. The motor shaft 5 carries a coupling 6, connected to a stub shaft 7, mounted in a housing 8. A pinion 9 (see Fig. 2) is mounted on this stub shaft and drives an intermediate gear or pinion 10 mounted on an intermediate shaft 11. The gear 10 meshes with a gear 12 mounted on a main drive shaft 13. The drive shaft is provided with a fly wheel 14 and with an electric clutch 15 (see Fig. 1). A brake drum 16 is mounted on the shaft beyond the electric clutch and is adapted to be engaged by a brake

band 17 controlled by a magnet or solenoid 18. The drive shaft 13 is also provided with a pair of pinions 19 each of which meshes with a gear 20 mounted on a crank shaft 21. The crank shaft 21 drives a crank arm 22 (see Fig. 3) which is connected to a vertical, reciprocating slide 23. This slide works in upper and lower guide members consisting of castings 24 and 25 carried by the upper and lower castings 2 and 1, respectively. The castings 24 and 25 may be provided with wear plates or facings 26 adapted to be engaged by the slide. Intermediate its ends the slide is provided with a rectangular opening for the reception of a pair of bearing blocks 28. These bearing blocks are adjustable by means of a wedge 29 having suitable adjusting means 30. Each side of the slide is provided with a pair of bearings 31 (see Fig. 4) adapted to receive a pin 33. A link 34 is carried by each of the pins 33. As shown, the link is provided with an opening adjacent its end for the reception of the pin and a bushing 32 which surrounds the pin. The end of the link is rounded and adapted to be received in a concave recess in the bearing block 28. One of the links 34 is connected to a rear slide 35 which is adapted to reciprocate on a suitable bed at right angles to the vertical slide 23. The bottom of the slide 35 engages a wear plate 36 and one side of the slide engages a portion of the housing. The other side engages a wedge-shaped wear plate 37, thus permitting adjustment and alignment of the slide. The face of the slide 35 is recessed to receive a bearing block 38 having a concave face and the end of the link 34 is rounded to engage the face of the bearing block. This end of the link is provided with an opening adapted to receive a bushing 40. A pin 39 extends through the bushing 40 and is received in bearings in the side walls of the rear slide 35. The bearing block 38 is also provided with an adjusting wedge 41 having suitable adjusting means 42. The other link 34 is similarly connected to a center slide 43 which is also recessed as herebefore described for the reception of a bearing block 44. The bearing block 44 is adjustable by means of a wedge 45 and wedge adjusting means 46. The bearing block 44 is shaped similar to the bearing block 38 and is also adapted to be engaged by the rounded end of the link 34. The link is also provided with an opening to receive a bushing in which is mounted a pin 47 which is received in bearings in the side walls of the center slide. By providing the bearing blocks 28, 38 and 44 the thrust of the drive from the vertical slide 23 to the rear slide 35 and center slide 43 is taken off the pins 33, 40 and 47 and transmitted through the bearing blocks and the links to the slides. The bearing blocks may be adjusted when necessary, through their respective wedges to retain the rounded ends of the links 34 in contact with the concave

faces of the bearing blocks so that the thrust is conveyed through the bearing blocks to the slides.

A front slide 48 is connected to the rear slide 35 to reciprocate therewith. The center slide is provided with openings adjacent each corner (see Fig. 5) through which pass tie rods 49 and these tie rods are surrounded by tubes 50. These tubes enter openings in the front and rear slides and engage shoulders 51 formed by a reduction in the size of the opening. The rods extend through the reduced portion of the openings as indicated at 52 in Fig. 4 of the drawings and are provided with nuts 53 on their ends. The front and rear slides are thus tied together by the rods 49 and tubes 50. Before assembling the rods 49 are heated, and they are placed in the tubes 50 and tied together while still hot. The rods contract on cooling and the tubes are thus placed under an initial compression equal to the force applied to the punches carried by the slides.

The main drive shaft 13 is also provided with a bevel gear 54 (see Fig 2) meshing with a bevel gear 55 on a shaft 56. The end of the main shaft and the gears 54 and 55 are mounted in a housing 57. The shaft 56 extends downwardly at an angle through a housing 58 into a housing 59 at the front of the machine. The lower end of shaft 56 is provided with a bevel gear 60 meshing with a bevel gear 61 mounted on a cam shaft 62.

The center slide 43 and the front slide 48 are provided with tool holders 74. The tool holders are mounted on the slides by means of a tongue and groove and are capable of being adjusted to properly center them.

A stripper block 89 is mounted in front of each of the tool holders. Each of the stripper blocks is provided with a plurality of concentric openings, preferably four in number, and a supporting stud passes through each of these openings and is received in an aligned opening in the tool holder.

A dial 98 is arranged between the pair of stripper blocks (see Fig. 3).

A link 360 may be connected to the bottom of the vertical slide 23 and this link is connected to a bell crank lever 361 pivotally mounted as at 362 in a bracket 363 carried by the lower casting. The other end of the bell crank lever is connected to the connecting rod 364 of a piston 365 which is mounted in a cylinder 366 arranged on the casting 1. The cylinder is provided with a plurality of air ports 367 arranged at a distance from the head of the cylinder so that the outward movement of the piston will trap a body of air in the cylinder and cushion the movement of the slides. The piston may be provided with a water jacket 368 having an inlet pipe 369 and an outlet pipe 370 for cooling it. This mechanism serves to store up the unused energy of the upstroke and

give it off on the down stroke, thereby adding to the power of the down or working stroke. This results in considerable gain in machine efficiency and higher speed is attained.

On the outward movement of the front slide 48 the nuts 53 on the ends of the tie rods move to a point beyond the vertical plane of the supporting casting 126. The casting is provided with openings through which the ends 10 of the rods and the nuts pass and these openings are provided with cover members 371 which are substantially cup-shaped and the bottoms of which are spaced from the supporting casting 126. These cover plates may 15 be secured in position by bolts 372 passing through aligned openings in ears 373 of the cover plates into openings in the casting. These cover plates prevent the oil used in lubricating the dial and its associated parts 20 from entering the housing of the cam shaft 62 and mixing with the lubricating oil employed in this portion of the machine.

We claim:

1. In a nut making machine, a front slide, 25 a center slide, said slides being reciprocal in independent paths, tool holders carried by said slides, a rear slide connected to said front slide, a vertical slide arranged between said rear slide and said center slide and links 30 connecting said rear slide and center slide to said vertical slide to reciprocate them in opposite directions.

2. In a nut making machine, a front slide, 35 a center slide, said slides being reciprocal in independent paths, tool holders carried by said slides, a rear slide arranged adjacent said center slide, rods connecting said rear slide and said front slide, compression tubes surrounding said rods, a vertical slide ar- 40 ranged between said rear slide and said center slide, and links connecting said rear slide and said center slide to said vertical slide to reciprocate them in opposite directions.

In testimony whereof we affix our signa- 45 tures.

SAMUEL W. AVIS.
MALCOLM H. AMES.
